UNITED STATES PATENT OFFICE.

SAMUEL B. FIELD, OF HOLBROOK, MASSACHUSETTS, ASSIGNOR OF ONE-FOURTH TO PNEUMATIC SCALE CORPORATION, OF QUINCY, MASSACHUSETTS, A CORPORATION OF MAINE, AND THREE-FOURTHS TO WILLIAM DOBLE, OF QUINCY, MASSACHUSETTS.

HOLLOW PANEL.

1,284,281.

Specification of Letters Patent. Patented Nov. 12, 1918.

Application filed July 22, 1918. Serial No. 246,240.

To all whom it may concern:

Be it known that I, SAMUEL B. FIELD, a citizen of the United States, residing at Holbrook, county of Norfolk, State of Massachusetts, have invented a certain new and useful Improvement in Hollow Panels, of which the following is a specification, reference being had therein to the accompanying drawings.

- 10 The invention relates to a new and useful improvement in hollow panels composed of two parallel plates forming the respective faces of the panel and an interposed truss plate which is united to the two face plates.
- 15 The invention is especially intended to be applied in the construction of panels for use in making boxes, more particularly that type of boxes in which the panels have hinged connection with each other so that
- 20 the box may be folded or knocked down, but the invention is not limited to use in connection with the manufacture of folding boxes, or even boxes of any character, as it is applicable to the construction of hollow
- 25 panels for any purpose in which strength and lightness are both desired. For convenience of illustration the drawings show the invention as applied to a box panel.

One object of the present invention is to

30 provide a double reinforcement by combining together two complementary reënforcing or truss plates to stiffen and brace the two face plates, and which are united in such manner as to stiffen and support each

35 other. Another object of the invention is to form the truss plate in spider form with radiating branches so arranged as to form strut portions and stiffening contact surfaces angularly arranged with relation to

40 each other for the purpose of giving greater stiffness than when the said branches are arranged parallel with each other.

The invention will be fully understood from the following description when taken in connection with the accompanying drawings and the novel features thereof will be pointed out and clearly defined in the claims at the close of this specification.

In the drawings, Figure 1 is a plan view

50 of a box panel constructed in accordance with the invention.

Fig. 2 is a plan view of a blank died out to proper shape from which to form one of the reinforcing or truss plates.

Fig. 3 is a plan view of the truss plate 55 formed out of the blank shown in Fig. 2 by turning up the side edges of each arm to form flanges, and with the metal around the central aperture drawn out to form an annular flange.

Fig. 4 is a section on line 4—4 of Fig. 3.

Fig. 5 is a section on line 5—5 of Fig. 3.

Fig. 6 is a section on line 6—6 of Fig. 1.

Fig. 7 is a section on line 7—7 of Fig. 1.

Referring now to the drawings, 1, 2 represent the two face plates of the panel which for convenience will be referred to as the upper and lower face plates respectively. The two truss plates are preferably formed nearly alike, there being a slight difference 70 in the width of the arms so that they may easily be shut together one over the other.

In the preferred form of construction each truss plate is formed out of a blank which is first died out in the shape shown 75 in Fig. 2, having a central body portion 3 from which there extend longitudinally at both ends in opposite directions, the two end arms 4, 5. There are also two oppositely extending arms 6, 7 which extend in a line 80 at right angles to the axis of the arms 4, 5. There is a diagonally extending pair of arms 8, 9 which extend in alinement with each other at an angle between the end arms 4, 5 and the cross arms 6, 7, and another 85 pair of diagonally extending arms 10, 11 in alinement with each other extending in opposite directions from the center of the body 3 whose axis crosses the axis of the arms 8, 9 at an angle, the arms 10, 11 forming 90 with the arms 8, 9 a cross shaped figure.

At the inner or junction ends of the arms 6, 7 with the body 3 there is formed at each edge a slot 12 which is not only cut into the edges of the arms 6, 7 but into one edge 95 of each of the diagonal arms 8, 9, 10 and 11. On each edge of the two longitudinal arms 4, 5 there is formed a slot 13 which also cuts into one edge of each of the diagonal arms 8, 9, 10 and 11 respectively. These 100 slots leave each arm with a laterally projecting flange portion on each edge which in the further shaping of the truss plate out of the blank may be turned at right angles to the plane of the plate as shown in Fig. 3 105 so that a cross sectional view through each arm will show a trough shape as in Fig. 5. The view in Fig. 5 shows particularly a

section through the arm 7, but this illustrates the trough or U-shaped appearance of each one of the arms in the portions where the flanges are turned up. In order to save 5 the employment of an unnecessarily large number of reference characters each one of the up-turned side flanges of the several arms is designated by 14.

In the middle of the blank shown in Fig. 10 2 there is formed an aperture 15. In the further shaping of the truss plate out of the blank the metal around this aperture is drawn out to enlarge the aperture and form an annular flange or lip 16 of the same 15 height as the side flanges 4 of the several arms.

In order that the truss plate may fit properly into a rectangular contour the outer edges of each diagonal arm 8, 9, 10 and 11 20 is formed with a beveled corner 17 in such manner that the beveled corners 17 of the arms 9, 10 will be in a straight line with the outer end of the cross arm 7, and the beveled edges 17, 17 of the arms 8, 11 will 25 be in a straight line with each other and with the end of the arm 6. The outer ends of the arms 9, 5 and 11 are all in a straight line and the outer ends of the arms 8, 4 and 10 are in a straight line with each other 30 so that the truss plate after the flanges have been bent up as shown in Fig. 3 will fit within a rectangular outline drawn around the ends of all the arms, such outline corresponding with the contour of the face 35 plates between which the truss is interposed.

Two truss plates, each complete as shown in Fig. 3, may be assembled together by placing them so that the flanges of the under plate extend upward and the flanges of the 40 lower plate extend downward as shown in Fig. 6, the annular flange 16 of one of said truss plates shutting down over the upwardly extending annular flange 16 of the other truss plate and the side edge flanges of the arms 45 of the upper truss plate shutting down over the upwardly extending side edge flanges of the arms of the lower truss plate so that when they are combined there will be a flat upper face and a flat lower face for the 50 combined truss plate. The flanges of one truss plate are seated upon the inner face of the companion truss plate, and the flanges of said companion truss plate are seated upon the inner surface of one of the face 55 plates.

As already stated the sheet metal of these truss plates may be sufficiently thin so that the flanges of one truss plate will shut down outside of the flanges of the other truss plate.

60 When the two companion truss plates have been assembled as described, they are placed between the two face plates 1, 2 as shown in Fig. 6 and the faces of the truss plates which contact with the two face plates are firmly 65 united together and also the overlapping

flange portions of the two truss members are firmly united together. They are preferably united by the so-called process of sweating which consists of a fusion of a soft metal coating on the contacting surfaces of the 70 two members or by soldering. It is important that the flanges be united together as well as that the face plates shall be united to the truss plates in order to make a perfectly firm union and prevent any spreading 75 apart of the flanges of the truss plates under pressure upon the outside of the face plates. The union between the parts is preferably performed by sweating or soldering or by welding because this makes the completed 80 panel virtually integral, but other forms of union may be employed and still come within the scope of the invention.

The interengaging annular flanges 16 of the two truss plates are united together as 85 well as the interengaging flanges of the spider arms. This union between the annular flanges may be effected at the same sweating operation as that by which the spider 90 arm flanges are united.

What I claim is :

1. A hollow panel comprising two face plates and an interposed truss composed of two plates each having spider arms formed with turned flanges which engage with corresponding flanges in the companion member of the truss, forming a hollow spider shaped truss with flat outside faces, the flat faces of the truss being united to the flat 95 faces of the face plate. 100

2. A panel comprising two face plates parallel with and spaced apart from each other and an interposed truss having spider arms formed with strut portions which extend across the space between the two plates and have flat faced portions some of which engage with one of the face plates and others of which engage with the other face plate, the contacting surfaces of the truss and face plates being firmly united together. 105 110

3. A panel comprising two face plates parallel with and spaced apart from each other and an interposed truss composed of two plates each having a body portion and arms extending in different directions therefrom in the same plane, each of said arms having flanges extending at right angles to the plane of the body of the plate, said truss plates being assembled facing in opposite directions to each other so that the flanges of one 115 truss plate interengage with the flanges of the other truss plate, the flanges of one truss plate being seated upon the inner face of the companion truss plate and the flanges of said companion plate being seated upon the inner surface of one of the face plates 120 when the parts are assembled, one of the outer faces of the combined truss engaging with the inner face of one of the face plates and the other outer face of the combined 125 130

truss engaging with the inner face of the other face plate, the contacting faces of the truss and face plates being firmly united together.

- 5 4. A panel comprising two face plates parallel with and spaced apart from each other and an interposed truss composed of two plates each having a body portion and arms extending in different directions therefrom
- 10 in the same plane, each of said arms having flanges extending at right angles to the plane of the body of the plate, the body of each truss plate being formed with an annular flange extending at right angles to the
- 15 plane of the body, said truss plates being assembled facing in opposite directions to each other so that the flanges of one truss

plate interengage with the flanges of the other truss plate, the flanges of one truss plate being seated upon the inner face of the 20 companion truss plate and the flanges of said companion truss plate being seated upon the inner surface of one of the face plates when the parts are assembled, one of the outer faces of the combined truss engag- 25 ing with the inner face of one of the face plates and the other outer face of the combined truss engaging with the inner face of the other face plate, the contacting faces of the truss and face plates being firmly united 30 together.

In testimony whereof I affix my signature.

SAMUEL B. FIELD.

Copies of this patent may be obtained for five cents each, by addressing the "Commissioner of Patents, Washington, D. C."

It is hereby certified that the names of the assignees in Letters Patent No. 1,284,281, granted November 12, 1918, upon the application of Samuel B. Field, of Holbrook, Massachusetts, for an improvement in "Hollow Panels," were erroneously written and printed as "Pneumatic Scale Corporation" and "William Doble", whereas said names should have been written and printed as *Pneumatic Scale Corporation, Limited*, and *William H. Doble*, as shown by the records of assignment in this office; and that the said Letters Patent should be read with this correction therein that the same may conform to the record of the case in the Patent Office.

Signed and sealed this 24th day of December, A. D., 1918.

[SEAL.]

F. W. H. CLAY,

Acting Commissioner of Patents.
